UNITED STATES PATENT OFFICE.

ALBERT F. ROBBINS, OF WALTHAM, MASSACHUSETTS.

JEWELER'S TOOL CHUCK AND HANDLE.

1,306,354.

Specification of Letters Patent. Patented June 10, 1919.

Application filed January 25, 1918. Serial No. 213,723.

To all whom it may concern:

Be it known that I, ALBERT F. ROBBINS, a citizen of the United States residing at Waltham, in the county of Middlesex and State 5 of Massachusetts, have invented certain new and useful Improvements in Jewelers' Tool Chucks and Handles; and I do declare the following to be a full, clear, and exact description of the invention, such as will enable others skilled in the art to which it 10 pertains to make and use the same.

My invention has for its object to provide a simple, inexpensive and efficient tool handle and chuck for jewelers' drills and 15 the like, which may be employed for holding drills and other tools of various sizes; and with this object in view, the invention resides in the novel construction herein described and claimed and shown in the accompanying drawing wherein;

Figure 1 is a side elevation;

Fig. 2 is a longitudinal section;

Fig. 3 is a transverse section on the plane of the line 3—3 of Fig. 2;

Fig. 4 is an end elevation looking in the direction of the arrows 4—4 of Fig. 2;

Fig. 5 is a perspective view of one of the tool holders;

Fig. 6 is a transverse section on line 6—6 30 of Fig. 5; and

Fig. 7 is a sectional view of one of the jaw contracting caps.

In the drawing above briefly described, the numeral 1 designates a straight elongated handle preferably of cylindrical shape 35 with reduced threaded ends 2, the greater part of said handle being suitably roughened to insure a firm grip in the hand. Each end of the handle 1 is formed with a longitudinal bore 3 of either uniform or different diameters and as shown, these bores may 40 be connected by a smaller bore 4.

In each bore 3 is an elongated cylindrical tool holder 5 having conical ends 6, the two 45 halves of said holders being formed with longitudinal bores 7 of different diameters to receive different sized drills and the like. A suitable number of longitudinal slits 8 lead from the intermediate portion of each 50 holder 5 through the ends thereof to form a plurality of tool gripping jaws or fingers 9 at each end of the holder. These jaws may be contracted around the tools by caps 10 whose closed outer ends are formed with 55 openings 11 partly receiving the conical

outer ends 6 of the holders. The slits 8 at one end of the holder 5 are staggered with respect to those at the other end to form yielding necks connecting the two sets of jaws.

No two bores 7 are of the same diameter and it will thus be seen that by removing the caps 10 and reversing the holders 5, a bore of any required size may be positioned for use, thereby adapting the device to all of 65 the usual different sizes of drills and the like.

From the foregoing and the accompanying illustration, it will be seen that although my invention is of simple and inexpensive 70 nature, it will be highly efficient and desirable. The exact construction shown has proven very effective and is preferably employed, but within the scope of the invention as claimed, numerous minor changes may 75 well be made.

I claim:

A jeweler's tool chuck comprising an elongated handle having a central bore of uniform diameter throughout its length, said 80 bore opening at one end through the front end of the handle and terminating at its other end in a flat bottom within said handle, a one-piece tubular tool holder received in said bore and of uniform diameter 85 throughout its length with the exception of its ends, said ends being conical, the bore of said tool holder being of different diameter at one end than at the other end to receive tools of different size, said holder having longitudinal slits leading from its center through its ends and dividing said holder into two sets of jaws, the slits of one end of the holder being staggered with respect to those of the other end to form yielding necks 90 connecting the two sets of jaws, and a tubular cap threaded on the end of said handle and having in its outer end an opening for receiving either conical end of the aforesaid holder to contract the jaws of such end upon 95 the tool, the other jaws then resting squarely against said bottom of the handle bore.

In testimony whereof I have hereunto set my hand in the presence of two subscribing witnesses.

ALBERT F. ROBBINS.
